COOLING SYSTEM FOR INDUSTRIAL OVENS
OF THE CONVEYER TYPE

Carl F. Mayer, Lakewood, Ohio

Application May 20, 1948, Serial No. 28,078

5 Claims. (Cl. 34—66)

1

This invention pertains to industrial ovens of the conveyor type that are used for drying cores or molds, or for heat treating articles of manufacture, or for drying or baking surface coatings thereon, such as enamel.

In industrial ovens of the conveyor type, provisions are usually made for cooling the work to convenient handling temperatures as the work approaches the unloading station, some consideration being given, also, to the comfort of the workmen who remove the work from the conveyors.

My present invention relates to cooling means for industrial ovens, particularly of the vertical type, and its principal object is to provide a cooling system that is reliable and efficient in cooling the work and that maintains a temperature atmosphere in the region of the unloading station.

Another object of my invention is to provide a cooling system for industrial ovens that includes refrigeration means by which the cooling fluid is chilled.

A related object is to make the refrigeration means variable as to its cooling capacity, and auxiliary to the air supply for the cooling system, so that artificial cooling may be dispensed with when the natural temperature of the air is sufficiently low to serve the purpose, or so that the effect of the refrigeration means may be modified, to attain the desired drop in temperature of the air.

Another object of the invention is to provide cooling equipment for a conveyor type oven by which the cooling fluid is well distributed and apportioned along the path of movement of the work as the latter approaches the unloading station, and by which the fluid is promptly withdrawn after passing about the work so that any obnoxious odors or injurious gases given off by the work during its passage through the cooling zone are quickly and effectively disposed of. Another and related object is to extend the area of the fluid withdrawing means beyond the cooling zone and into the region of the unloading station, thereby to render the atmosphere in which the operators work more wholesome and comfortable.

A further object is to provide air impelling means opposite the unloading door or opening of the oven for supplying fresh air immediately in the region of said door or opening.

A still further object of the invention is to provide the cold air supply duct of the system with a series of outlet passages that are stepped along the path of movement of the work and which

2

openings are equipped with regulating means or shutters by which the effective cross sectional area of said passages may be varied thereby to better distribute and apportion the cooling fluid along said path.

It is another object of my invention to improve the operation of the oven, generally, by incorporating an injector in the exhaust flue of the oven that is supplied with motive fluid from the discharge end of the cooling system.

Because of the character of the invention itself, and the huge size of ovens of the kind in which it is incorporated, I have illustrated the invention in a somewhat diagrammatic way in the accompanying drawings; and as I proceed to describe the invention by reference thereto, utilizing like reference characters to designate like parts in the several views, objects and advantages additional to those above enumerated will become apparent.

20 In the drawings, Fig. 1 is an elevational view of an industrial oven of the vertical type equipped with the cooling system of my invention, the oven being viewed from the unloading side; Fig. 2 is an elevational view of the oven as 25 though looking from the right of Fig. 1; Fig. 3 is a similar view, looking from the opposite side of Fig. 1; Fig. 4 represents a vertical section through the oven, substantially on the line 4—4 of Fig. 1, and Figs. 5, 6 and 7 are horizontal sections, taken on the respective lines 5—5, 6—6 and 7—7 of Fig. 1.

The present oven comprises a front wall 1, a rear wall 2, side walls 3 and 4, and a top wall 5. The parts of these walls that enclose the heated chamber A in which the work is dried or otherwise treated, are, in practice, constructed of sections of suitable size, each consisting of a large slab or flat body of insulating material enclosed in sheet metal, and the sections are suitably joined and held together within a framework that is made up of standard structural elements such as channels, I-beams, etc., the framework being designated generally by the reference character 10. The oven structure rises from the bottom of a pit 11 of suitable depth below the level of the floor 12.

The bottom of the heated chamber A is something more than head height above the floor 12, and below said chamber the front wall is fabricated of metal plates 14 that are spaced apart vertically to provide therebetween a loading door or opening B, while the corresponding portion of the rear wall is made up of similarly arranged metal plates 15 between which is an unloading door or opening C.

Extending laterally from the sides of the oven structure, at about the level of the bottom of the heated chamber A, and constituting parts of the general framework 10, are platforms 20 and 21. In the plane of these platforms, a bridge 22 extends transversely through the oven and supports a heater 25, desirably of the gas, liquid fuel or powdered coal burning type, and constructed to provide a fluid circulating space, according to prior practice. Rising from the rear edge of this bridge, in suitably spaced relation to the wall 2, is a heat insulating partition 26. 27 is a wall, which may be constructed of metal plate, that rises from the top of the heater 25 in forwardly spaced relation to the partition 26 so as to define therewith a so-called recirculating duct 28 that opens at its lower end into the fluid circulating space of the heater 25. Shown as rising from the side of the heater opposite the recirculating duct, are two heat supply ducts 30. Obviously, one broad supply duct might be utilized in place of the two shown. Supported upon the platform 21 is a heat supply fan or blower 32, shown as adapted to be driven, through suitable connections 33, by an electric motor 34. The inlet of the fan or blower 32 is placed in communication, through a conduit 35, with the fluid circulating space of the heater 25, while a conduit 36 leads upwardly from the outlet of said fan or blower and thence laterally through the adjacent side wall 4 of the oven and has communicative connection with the beforementioned heat supply ducts 30, as shown at 37 in Fig. 4. Outlet openings 38 are spaced apart vertically of the sides of the supply ducts that face the front wall 1 of the oven.

Thus it will be seen that when the fan or blower 32 is in operation, hot gases will be drawn from the fluid circulating space of the heater 25 and delivered to the ducts 30 from which it will be projected substantially horizontally across a part of the heated chamber A that may be termed the drying or treating area. Also by the action of the fan or blower 32, suction is created within the fluid circulating space of the heater 25 so as to withdraw air from the top portion of the heated chamber A through the recirculating duct 28. It may be mentioned, however, that in the operation of the heater, a certain amount of atmospheric air is continually drawn in and added to that returned from the heated chamber, and this surplus fluid is withdrawn from the top of the oven through ducts 40 that open through the rear wall 2 adjacent the top of the oven and communicate with a stack 41.

Included in the general framework 10, near the top of the oven, are platforms 44 and 45 that support the respective bearings 46 and 47 on opposite sides of the oven. Disposed transversely of the oven and extending outwardly through holes in the side walls 3 and 4 is a shaft 50 that is journaled in said bearings, and secured to the shaft beyond the bearing 47 is a gear 53 that meshes with a driving pinion 54. This pinion constitutes a part of driving mechanism designated generally by the reference numeral 55. Fastened to the shaft 50, inside the oven, and in close proximity to the side walls 3 and 4, are large sprocket wheels 60 about which endless conveyor chains 61 are engaged. The sprocket wheels are rotated in the direction indicated by the arrow in Fig. 4 to propel the chains upwardly adjacent the front wall of the oven and downwardly adjacent the rear wall thereof.

The chains are restrained against appreciable sway from front to rear of the oven in the region of the loading and unloading openings B and C, respectively, by guides 64, and at their lower ends the conveyor chains pass through guiding means 65. Cross bars 67 are supported at their ends by the opposed chains 61 and suspended from each bar is a rack 70 that carries the cores, molds, or other articles that are to be dried, baked or heat treated.

The work descends adjacent the rear wall 2 through what may be termed the cooling area or zone enclosed by the partition 26 and the adjacent portions of the rear and side walls of the oven. Supported by the framework on the outer side of the rear wall 2, substantially throughout the area of the cooling zone is a cold air supply duct 80. Passages 81 lead therefrom through the rear wall 2. Flow of air through the passages 81 is adapted to be controlled by dampers 84 that are adjustable by any suitable means. Thus, the supply of cold air to the cooling zone may be properly regulated and distributed from top to bottom thereof. Air is conveyed to the top of the duct 80 by a conduit 85 that leads from the outlet of a cold air supply fan or blower 86, mounted on a platform 87 that extends laterally from the oven beyond the side wall 4 a suitable distance below the plane of the platforms 44 and 45. The inlet of the cold air fan or blower 86 communicates through an outwardly flaring casing 88 with the evaporator housing 89 of refrigeration apparatus designated generally by the reference numeral 90.

It will be understood that the evaporator housing 89 has an opening or openings through which atmospheric air is drawn by the action of the fan or blower 86. The evaporator is made up of a plurality of units that may individually be thrown into and out of operation wherefore the cooling capacity of the refrigeration apparatus may be varied at will. Therefore, refrigeration may be supplied as required to chill the air to the desired degree of coolness; or all units of the evaporator may be rendered ineffective when the atmospheric temperature is low enough to need no chilling.

Situated along the outer sides of the walls 3 and 4 are recovery ducts 95. These ducts are of substantially the same dimension, in a direction from front to rear of the oven, as the cooling zone; and they extend upwardly from about the plane of the platforms 20 and 21 to an elevation above the top plane of the cold air supply duct 80 where they curve rearwardly and join a transverse conduit 96. As best shown in Fig. 6, the conduit 96 extends forwardly, adjacent the wall 4, to and communicates with the inlet of an exhaust fan or blower 100. This fan or blower is operated, through driving connections 101, by an electric motor 102. This equipment is mounted on the platform 87, along with the refrigeration apparatus and the cold air supply fan or blower. A conduit 105 leads from the outlet of the exhaust fan or blower 100 rearwardly and upwardly to where it has connection with a pipe 106 which extends through the adjacent side of the stack 41. Inside the stack, the pipe is extended upwardly, axially of the stack, and is shown as convergent at its upper end, to form an injector nozzle 107. It is apparent, therefore, that when the exhaust fan or blower is in operation a suction will be created that will enhance the natural draft of the stack 41 and thus more effectively draw off the surplus gases

from the top of the oven through the previously mentioned passage 40.

For the same and obvious reason that the cold air supply duct 80 becomes progressively smaller in cross section as it extends downwardly along the cooling zone, the ducts 95 taper downwardly; and these latter ducts communicate with the cooling zone through passages 110.

Attention is particularly directed to the fact that the recovery ducts 95 extend below the cooling zone, and substantially to the plane of the platforms 20 and 21, as casually mentioned hereinbefore. This insures withdrawal of heated gases and odors given off by the work in the region of the unloading opening C. Also recovered by the extended portions of the ducts 95 are hot gases that may drift down from the cooling area or zone. However, to insure the maximum of comfort to the workmen employed at the unloading station, I seal off the space inwardly of said opening from the portion of the oven beneath the bridge 22 by a heat insulating baffle wall 115. This baffle wall extends in a transverse direction from one to the other of the side walls of the oven and vertically between said bridge 22 and the level of the floor 12. This wall may be provided with one or more openings 116 that are occupied by ventilating fans 117, driven by electric motors 118. The air supplied to these fans tends to check any downward drift of heated gases from above, and cools that portion of the unloading zone that is faced by the workers in front of the opening C.

From the foregoing description, it will be seen that my invention provides a cooling system for industrial ovens of the conveyor type that effectively cools the work as it approaches the unloading opening or station and maintains a comfortable atmosphere in the region of such opening or station. Since the work is cooled to a proper handling temperature and hot obnoxious gases are eliminated from the vicinity of the unloading station, the workmen will naturally perform more efficiently, and processing of the articles will be expedited. The system, as herein disclosed, also provides for regulating the temperature of the cooling air below that of the atmosphere, and for effecting proper distribution of said air along the course of movement of the work.

Having thus described my invention, what I claim is:

1. A cooling system for vertical industrial ovens of the conveyor type, which ovens are characterized by a walled structure having an opening providing an unloading station and enclosing a space above said station serving as a cooling zone and through which zone and past which station a flight of the conveyor descends; said cooling system comprising means adjacent the walled structure above said opening and substantially coextensive in area with said zone for delivering cooling air to the zone, and means adjacent the sides of the walled structure and extending downwardly from the top of the cooling zone and continuing through the region of the unloading station for withdrawing gases from said zone and region simultaneously with the delivering of the cooling air to said zone, the last mentioned means exhausting said gases from the system, a baffle wall within and extending transversely of the walled structure for closing off said region from the adjacent portion of the interior of said structure, said baffle wall having a ventilating opening,

and air impelling means for creating a draft of air through said opening.

2. A cooling system for vertical industrial ovens of the conveyor type, each of which ovens includes side walls and a rear wall, the latter having an unloading opening, and the oven including a partition extending between the side walls and spaced from the rear wall above the plane of said unloading opening to set off within the oven a cooling zone through which, and past said opening, a flight of the conveyor descends; said cooling system comprising a cold air supply duct supported on the outer side of said rear wall and being substantially coextensive in area with the cooling zone, said rear wall and the duct having a series of passages through which the duct communicates with the cooling zone, means for supplying cooling air to said duct, refrigeration means for chilling said air, ducts supported on the outer side of the side walls of the oven and extending downwardly from about the top plane of the supply duct a distance below the bottom plane of the said supply duct so as to have parts disposed on opposite sides of the region of the unloading opening, the side walls of the oven and the ducts adjacent thereto having passages through which the said ducts communicate with the cooling zone and said region, and fluid impelling means having an inlet in communication with the upper ends of the second mentioned ducts for withdrawing gases therefrom.

3. A cooling system for vertical industrial ovens of the conveyor type, each of which ovens includes side walls and a rear wall, the latter having an unloading opening, and the oven including a partition extending between the side walls and spaced from the rear wall above the plane of said unloading opening to set off within the oven a cooling zone through which, and past said opening, a flight of the conveyor descends; said cooling system comprising a cold air supply duct supported on the outer side of said rear wall and being substantially coextensive in area with the cooling zone, said rear wall and the duct having a series of passages through which the duct communicates with the cooling zone, means for supplying cooling air to said duct, further means for severally controlling the amount of air flowing through said passages, ducts supported on the outer side of the side walls of the oven and extending downwardly from about the top plane of the supply duct a distance below the bottom plane of the said supply duct so as to have parts disposed on opposite sides of the region of the unloading opening, the side walls of the oven and the ducts adjacent thereto having passages through which the said ducts communicate with the cooling zone and said region, and fluid impelling means having an inlet in communication with the upper ends of the second mentioned ducts for withdrawing gases therefrom.

4. A cooling system for vertical industrial ovens of the conveyor type, each of which ovens includes side walls and a rear wall, the latter having an unloading opening, and the oven including a partition extending between the side walls and spaced from the rear wall above the plane of said unloading opening to set off within the oven a cooling zone through which, and past said opening, a flight of the conveyor descends; said cooling system comprising a cold air supply duct supported on the outer side of said rear wall and being substantially coextensive in area with the cooling zone, said rear wall and the duct having a series of passages through which the duct

communicates with the cooling zone, means for supplying cooling air to said duct, ducts supported on the outer side of the side walls of the oven and extending downwardly from about the top plane of the supply duct a distance below the bottom plane of the said supply duct so as to have parts disposed on opposite sides of the region of the unloading opening, the side walls of the oven and the ducts adjacent thereto having passages through which the said ducts communicate with the cooling zone and said region, fluid impelling means having an inlet in communication with the upper ends of the second mentioned ducts for withdrawing gases therefrom, a baffle wall spaced inwardly from that portion of the rear wall having the unloading opening and being in substantially the vertical plane of the aforesaid partition, said baffle wall having a ventilating opening, and an air impeller for creating a draft of air through said opening.

5. A cooling system for vertical industrial ovens of the conveyor type, each of which ovens includes side walls and a rear wall, the latter having an unloading opening, and the oven including a partition extending between the side walls and spaced from the rear wall above the plane of said unloading opening to set off within the oven a cooling zone through which, and past said opening, a flight of the conveyor descends; said cooling system comprising a cold air supply duct supported on the outer side of said rear wall and being substantially coextensive in area with the cooling zone, said rear wall and the duct having a series of passages through which the duct communicates with the cooling zone, means for supplying cooling air to said duct, regulable refrigeration means for chilling said air, ducts supported on the outer side of the side walls of the oven and extending downwardly from about the top plane of the supply duct a

distance below the bottom plane of the said supply duct so as to have parts disposed on opposite sides of the region of the unloading opening, the side walls of the oven and the duct adjacent thereto having passages through which the said ducts communicate with the cooling zone and said region, fluid impelling means having an inlet in communication with the upper ends of the second mentioned ducts for withdrawing gases therefrom, a baffle wall spaced inwardly from that portion of the rear wall having the unloading opening and being in substantially the vertical plane of the aforesaid partition, said baffle wall having ventilating openings, and an air impeller in operative relation to each of said openings.
